ATTORNEY.

UNITED STATES PATENT OFFICE.

LEVI D. VAN VALKENBURG, OF HOLYOKE, MASSACHUSETTS.

RETAINER FOR FOUNTAIN-PENS AND PENCILS.

1,095,685.

Specification of Letters Patent.

Patented May 5, 1914.

Application filed January 18, 1913. Serial No. 742,757.

To all whom it may concern:

Be it known that I, LEVI D. VAN VALKENBURG, a citizen of the United States of America, and resident of Holyoke, in the county of Hampden and State of Massachusetts, have invented certain new and useful Improvements in Retainers for Fountain-Pens and Pencils, of which the following is a full, clear, and exact description.

10 This invention relates to clips or retainers to be used on fountain pens and pencils for engagement with the edge portion of a vest or other pocket whereby the loss of a pen or pencil is prevented.

15 The invention especially pertains to a device of the general character mentioned which has a lever-like operating member by means of which, under the exertion of pressure, the bill or retaining part of the device 20 is forced to its open or pocket disengaging position for facilitating the engagement of the retainer with the edge of the wall or leaf of the pocket and also its disengagement.

The object of the invention is to provide 25 a retainer for fountain pens and pencils which is extremely cheap of manufacture, which may be made from a single blank of spring sheet metal under very few mechanical operations, which is durable and capable 30 of being used for a long time without impairment, which is entirely efficient and reliable in service, and which may be of slighty and attractive appearance.

35 The invention is described in conjunction with the accompanying drawings and is set forth in the claims.

In the drawings:—Figure 1 is a perspective view, enlarged, of the retainer as applied on the cap of a fountain pen. Fig. 2 40 is a longitudinal sectional view of the same, the retainer being shown in its normal position. Fig. 3 is a sectional view similar to Fig. 2, but showing the retainer as in its 45 opened or disengaged position. Fig. 4 is a cross sectional view still further enlarged, taken on line 4—4, Fig. 2.

In the drawings, the device is represented as consisting of a spring blade A having at the rear end thereof a spring band B to 50 constrictively encircle a fountain pen or pencil and to serve as a clip for the holding of the device on the pen or pencil.

The spring blade is provided at its forward end with a projection d which extends 55 transversely toward and is adapted for bearing against the side of the pen.

The blade A has a recess-forming incision extending from its intermediate portion well to the rearward whereby a lever-forming tongue g is produced, such tongue being bent to an outward and rearward inclination relatively to the plane of the blade; and it has its portion i which is within the recess k and adjoining the blade proper inwardly bent on a rounding curve to form a fulcrum bearing portion which has contact against the side of the pen or pencil.

Inasmuch as the lateral projection d outwardly offsets the extremity of the blade or bill of the retainer, and such blade lies in a plane slightly angular to the longitudinal line of the pen or pencil, the slight inward offsetting of the portion of the blade indicated at i is advantageous inasmuch as a constant fulcrum bearing of the lever member against the side of the pen is assured.

In action, when pressure is applied at the rear and outwardly extended extremity of the lever member g, the blade is caused to be swung to the open position shown in Fig. 3, it being free and resilient from its forward extremity to its point of junction at x with the encircling band or clip B.

As apparent, from the inspection of the drawings, the device is susceptible of being manufactured from a stamping of spring sheet metal with great rapidity and cheapness and with the requirement of but very few mechanical operations.

I claim:—

1. A device of the character described consisting of a spring blade having at the rear end thereof a spring band to constrictively encircle an instrument, provided at its forward end with a projection which extends transversely thereof, and having an incision extending from its intermediate portion rearwardly whereby a lever forming tongue is produced, said lever being bent to an outward and rearward inclination relatively to the blade, and said lever forming tongue at its portion which is within the incision and adjoining the blade proper having a fulcrum adapted to bear against the side of the instrument.

2. A device of the character described consisting of a spring blade having at the rear end thereof a spring band to constrictively encircle an instrument, provided at its forward end with a projection which extends transversely thereof, and having a recess-forming incision extending from its inter-

mediate portion rearwardly whereby a lever forming tongue is produced, such tongue being bent to an outward and rearward inclination relatively to the blade, and having its portion which is within the recess and adjoining the blade proper inwardly bent on a rounding curve to have a fulcrum bearing against the side of the instrument.

3. An article of manufacture consisting of 10 a lever operated instrument retainer formed out of one piece of material and consisting of an instrument gripping band and a depending tongue having a lever stamped out of the same and bent outwardly of the

tongue, the lever having a curved fulcrum 15 connecting the same to the tongue and adapted to bear against the side of the instrument through the slot formed by said lever and the free end of the lever projecting outwardly and upwardly toward the band, said 20 slot terminating above the forward end of the tongue.

Signed by me at Springfield, Mass., in presence of two subscribing witnesses.

LEVI D. VAN VALKENBURG.
